HANDKERCHIEF PACKET

Daniel S. Warner, Buffalo, N. Y.

Application May 15, 1940, Serial No. 335,307

9 Claims. (Cl. 206—57)

This invention relates to packets, and more particularly to an improved form of handkerchief packet containing a plurality of tissue sheets and being adapted to be carried in a relatively flat enclosure such as a side pocket of a man's dress coat, or the like.

One of the objects of the invention is to provide a packet of the type described which comprises in combination a container and plurality of tissue sheets disposed in the container in a novel and improved manner whereby the tissue sheets may be successively removed from the container with improved facility without removing the container from the carrying pocket or the like and through use of only one hand of the user and in such manner as to simulate the simple withdrawing of a free handkerchief from the carrying pocket. Another object of the invention is to provide a packet of the character described which is of improved form so as to be adapted to conform to the shape of a man's dress coat pocket in an improved manner. Other objects and advantages of the invention will appear from the specification herein.

In the drawing:

Fig. 1 is a perspective of a handkerchief packet of the invention;

Fig. 2 is a similar perspective of another form of the invention;

Figs. 3, 4 and 5 are typical vertical sections through a group of tissue sheets disposed in various forms of assembly arrangements within the sheet container element of the invention; and

Fig. 6 is a fragmentary diagrammatic illustration of an operation in connection with the use of the invention.

As illustrated in Fig. 1, the packet of the invention comprises essentially a relatively thin rectangular box-like container 10 formed of folded cardboard, or the like, and comprising a structure having generally front and rear walls 12 and 14, respectively; end walls 16 and 18; and a bottom closure wall 20. The sheet material from which the container 10 is formed may be initially cut out by a single blanking operation and then folded into the form illustrated in the figure. In connection with the blanking process the end wall portion 16 may be provided with an integral laterally extending flap 22 which is adapted to a lap under the adjacent side edge portion of the front wall 12 when the latter is folded into assembly position. An application of adhesive between the flap 22 and the front wall 12 will then provide the necessary

connection therebetween to maintain the folded structure in assembled relation. Similarly, the bottom wall 20 may be provided with an extending flap portion adapted to coact with a main wall portion of the structure for maintaining the wall 20 in bottom closing position upon the container 10.

The upper edge of the front face 12 is recessed as at 24 along a line inclined relative to the major marginal edges of the structure, and is provided therewith along with an inturned flap 26 which extends into the interior of the container for a purpose that will hereinafter be explained. As illustrated in Figs. 3, 4 and 5, the tissue sheets 30 of the invention are installed within the container in accordion pleated or S folded manner. In assembling the packet the tissue sheets 30 are first arranged in superposed relation to form a pack and then the pack is folded as at 32 and 34. The folding is so performed in each case as to dispose the lower end 36 of the sheet pack at about the level of the fold 32, but the upper end 38 of the sheet pack is arranged to extend a substantial distance above the line of the fold 34. The fold 34 is so arranged as to be disposed beneath the inturned flap 26 of the container 10 when the parts are in completely assembled form. The edges of the sheets 30 at the lower end 36 of the pack are semi-permanently attached to the lower end of the container 10 by means of a staple 40; and the edges of the sheets 30 of the upper end 38 of the sheet pack are disposed within the confines of the upper portion of the container body. As illustrated in Fig. 1, a top closing flap 28 may be provided if desired as an integral extending portion of the back wall 14 of the container for folding forwardly and downwardly and insertion between the upper end of the sheet pack and the front face 12 of the container to provide a folding cover for the open end of the container.

Fig. 2 illustrates another form of the sheet pack container wherein the container structure is formed by simply folding a generally rectangular piece of cardboard or the like at two parallel lines 52 and 54 and joining the converging ends of the blank by arranging them in lapped relation and cementing or stapling or otherwise connecting the portions together. The lower end of the container 50 may be closed by fastening the lower edges of the front and rear wall portions together in contiguous relation by means of staples 58, or any other suitable means. Thus, the container 50 comprises substantially a pair of opposed front and rear wall

members arranged in slightly spaced relation and joined at their side edge portions by means of relatively sharp folds in the container sheet material. As illustrated, the container front and rear walls are preferably concentrically curved in horizontal section so as to give the container a slightly arcuate sectional form; the degree of curvature of the walls being such that the container is adapted to be placed within the side pocket of a man's dress coat, or the like, and to conform substantially to the normal curvature of the pocket without bulging effects such as would destroy the smooth outer appearance of the pocket and coat line.

As in the case of Fig. 1, the front wall of the container 50 of Fig. 2 is recessed as at 60 and provided with an inturned flap 62 disposed above the upper fold of the sheet pack therein. A temporary closure in the form of a readily removable cap 70 is provided as a sanitary seal for the contents of the container until such time as they are to be used whereupon the cap 70 will be removed from the container. The cap 70 is in the form of a sleeve having a closed upper end and being adapted to fit upon the upper end of the container 50. It may be conveniently formed of Cellophane, paper, or any other suitable sheet material of inexpensive nature.

Figs. 3, 4 and 5 illustrate three possible forms of arrangements of the sheet elements 30 in their folded sheet pack form. In Fig. 3 the sheets are all of equal length and alternate sheets 30 are arranged in overlapping relation at their opposite ends so that at the end portions 36 and 38 every other sheet extends beyond the sheets therebetween. The staple 40 is then driven through only the extending sheet end portions at the bottom of the pack and into connected relation with the front wall of the container upon final assembly of the unit. Hence every other one of the sheet elements of the pack extends above the sheet element next adjacent thereto at the top end of the container and the user is enabled to readily grasp one sheet at a time between his fingers, commencing with the sheet presented toward the front face of the container. By simply pulling upon the upper end of each sheet it will first be pulled out of the lower fold 32 and then as it assumes unfolded condition the stress of the pull will be transmitted to the staple 40 and the sheet will tear away therefrom and be free to be completely withdrawn from the container without disturbing the other sheets of the pack. When the sheet elements of the pack are formed of certain kinds of material, such as crepe paper or the like, I have found that the method of sheet mounting illustrated in Fig. 3 is very satisfactory because the friction between adjacent nested sheet elements in the neighborhood of the staple 40 effectively retains all of the sheet elements in proper position during the process of removal of successive sheets from the pack.

In the case of use of other kinds of tissue material, however, it may be found desirable to individually fix all of the sheet elements to the container wall by means of the staple 40, and in such case the sheet pack will be arranged as illustrated in Figs. 4 and 5 wherein the lower edges of all of the sheet elements 30 are coextensive and clamped to the container wall by means of the staple. In Fig. 4 the upper ends of the sheets 30 are arranged in alternate overlapping relation by providing every other sheet of shorter length than the sheet next adjacent thereto, or as illus-

trated in Fig. 5, all of the sheets may be cut to equal length so as to make the upper ends thereof coextensive, as may be preferred.

Particular attention is called to the form of the recess in the container front wall of Fig. 1 wherein the recess is formed of increasing depth toward the side edge of the container diametrically opposed to the location of the staple 40. By reason of this arrangement the tension upon each sheet element during withdrawal operations is directed diagonally of the sheet as illustrated in Fig. 6. Thus, when the stress is transmitted to the connection between the staple 40 and the lower end of the sheet, the sheet tends to tear around the staple 40 in such manner as to leave a minimum amount of the sheet material in engagement with the staple after the sheet is severed therefrom.

It will be apparent that as the tissue sheets are drawn from the casing 10 (Fig. 1) or 50 (Fig. 2) the top line of fold 34 will abut the lower face of the inturned flap 26 of Fig. 1, or of the flap 62 of Fig. 2, thus preventing disturbance of the pack as a unit from its nested position in the container casing but without interfering with withdrawal of the sheet elements 30 individually therefrom.

If desired, the top closure flap 28 of Fig. 1 may be severed from the rear wall of the container just prior to use of the sheets, and the packet then inserted in the pocket of the user with the open end of the packet facing upwardly.

Thus, it will be apparent that I have provided an improved form of sheet pack and container therefor such as is particularly adapted for use in connection with the dispensing of crepe paper handkerchiefs, or the like. The container is so formed as to be adapted to be carried in a side coat pocket or the like and to conform to the natural contour thereof in an improved manner, and the sheet pack is so arranged that individual sheet elements thereof may be removed therefrom in an improved manner and with utmost convenience and facility and through use of only one hand of the user and without removing the container from the carrying pocket and in such manner as to simulate the simple withdrawing of a free handkerchief from the pocket.

It will be understood that the sheets 30 of the packet of the invention may be individually either in single or longitudinally folded form so that when they are withdrawn from the packet casing they may provide handkerchiefs or the like of any desired width. Thus, the dimensions of the packet casing may be kept down to convenient size for pocket carrying use, and yet the handkerchiefs contained therein may be provided of ample size for convenient use when unfolded after being withdrawn from the casing.

Although only a limited number of forms of the invention have been shown and described in detail, it will be apparent to those skilled in the art that the invention is not so limited but that various changes may be made therein without departing from the spirit of the invention or the scope of the appended claims.

I claim:

1. A handkerchief packet comprising a casing member or thin section and having a pair of major wall portions of slightly curving sectional form disposed generally in concentric spaced relation, an assembly of handkerchief tissue sheets disposed in superposed pack form and pack-folded in accordion pleated manner along two parallel lines of folding intermediately of

the ends of said sheets; said folded pack being nested within said casing with like end edges of said sheets adjacent the lower end of said casing and semi-permanently connected thereto to a wall portion of said casing by means of a point connection device, the other like end edges of said sheets being disposed adjacent the upper end of said casing for convenient access to the user.

2. A handkerchief packet comprising a casing member of thin section and having a pair of major wall portions of slightly curving sectional form disposed generally in concentric spaced relation, an assembly of handkerchief tissue sheets disposed in superposed pack form and pack-folded in accordion pleated manner along two parallel lines of folding intermediately of the ends of said sheets; said folded pack being nested within said casing with like end edges of said sheets adjacent the lower end of said casing and semi-permanently connected thereto to a wall portion of said casing by means of a point connection device, the other like end edges of said sheets being disposed adjacent the upper end of said casing for convenient access to the user, one of said major wall portions being recessed at the upper end thereof and provided with an inturned integral flange adapted to operate as a stop for preventing unfolding movement of said pack as a unit during sheet withdrawal processes.

3. A handkerchief packet comprising a casing member having side wall portions, an assembly of handkerchief tissue sheets disposed in superposed pack form and pack-folded in accordion pleated manner along two parallel lines of folding intermediately of the ends of said sheets; said folded pack being nested within said casing with like end edges of said sheets adjacent the lower end of said casing and semi-permanently connected thereto to a portion of said casing by means of a point connection device, the other like end edges of said sheets being disposed adjacent the upper end of said casing for convenient access to the user, one of said side wall portions being recessed at the upper end thereof along a line inclined with relation to the top marginal edge of said casing and provided with an integral inturned flange adjacent the lowest portion of said recess for cooperation with one of said folded portions of said pack to prevent the latter from being disrupted under sheet withdrawal processes.

4. A handkerchief packet comprising a casing member having side wall portions, an assembly of handkerchief tissue sheets disposed in superposed pack form and pack-folded in accordion pleated manner along two parallel lines of folding intermediately of the ends of said sheets; said folded pack being nested within said casing with like end edges of said sheets adjacent the lower end of said casing and semi-permanently connected thereto to a portion of said casing by means of a point connection device, the other like end edges of said sheets being disposed adjacent the upper end of said casing for convenient access to the user, one of said side wall portions being recessed at the upper end thereof along a line inclined with relation to the top marginal edge of said casing and provided with an integral inturned flange adjacent the lowest portion of said recess for cooperation with one of said folded portions of said pack to prevent the latter from being disrupted under sheet withdrawal processes, said point connection de-

vice being located at a position diametrically opposed to said lowest portion of said wall recess.

5. A sheet packet comprising a generally rectangular casing member having a dispensing opening, an assembly of sheets disposed in pack form and nested within said casing with like portions of said sheets disposed adjacent said dispensing opening of said casing and opposite like ends of said sheets being detachably connected to said casing at only a corner portion thereof opposite to said dispensing opening thereof, said casing being recessed at a wall portion thereof adjacent said dispensing opening and at only one location which is substantially diametrically opposed to the point of said detachable connection to provide convenient means of access to said sheet portions.

6. A sheet packet comprising a generally rectangular casing member having an open edge, an assembly of sheets disposed in pack form and nested within said casing with like portions of said sheets disposed adjacent said open edge and opposite like ends of said sheets being detachably connected to said casing at only one corner portion thereof opposite said open edge, said casing being recessed at a wall portion thereof adjacent said open edge and at only one location which is substantially diametrically opposed to the point of said detachable connection to provide convenient means of access to said sheet portions.

7. A handkerchief packet comprising a casing member having a pair of opposed side wall portions, an assembly of handkerchief tissue sheets disposed in pack form and pack folded in accordion-pleated manner along two lines of folding and nested within said casing member, said sheets being semi-permanently connected at their lower ends to said casing member by means of a point connection device, one of said side wall portions being recessed at the upper end thereof to provide an enlarged opening for convenient access to said sheets by the user, and an inwardly extending flange integral with said recessed wall portion adapted to overlap one of said lines of folding and to restrain pack unfolding stresses within said pack during withdrawal of individual sheets therefrom.

8. A handkerchief packet comprising a casing member having opposed side wall portions and bottom and end walls, an assembly of handkerchief tissue sheets disposed in pack form and pack folded in accordion-pleated manner along two lines of folding to provide three panel sections and nested within said chamber, one of the end panel sections having the marginal portions of the sheets directed downwardly and the other end panel section having the marginal portions of the sheets directed upwardly, said second mentioned panel section being of greater height than the other two panel sections whereby the upper marginal portions of the sheets extend upwardly beyond the remaining two panel portions, said side walls being substantially equal in height to the larger panel section, said sheets being semi-permanently connected at their lower marginal portions to said casing member, the side wall portion adjacent the lower marginal portions of said sheets being recessed at the upper end thereof to give access to the upper marginal portions of said sheets, and an inwardly extending flange at the lower edge of said recess adapted to overlie the two shorter panel portions to prevent disruption of pack folded rela-

tion of remaining sheets during withdrawal of individual sheets.

9. A handkerchief packet comprising a casing member of thin section and having a pair of major wall portions of slightly curving sectional form disposed generally in concentric spaced relation, an assembly of handkerchief tissue sheets disposed in superposed pack form and pack-folded in accordion pleated manner along two parallel lines of folding intermediately of 10 the ends of said sheets; said folded pack being nested within said casing with like end edges

of said sheets adjacent the lower end of said casing and semi-permanently connected thereto to a wall portion of said casing by means of a point connection device, the other like end edges of said sheets being disposed adjacent the upper end of said casing for convenient access to the user, and a detachable cover member slidably mounted upon the open end portion of said casing and adapted to function as a closure therefor and to protect said sheets against soil contamination.

DANIEL S. WARNER.
